[57] **CLAIM**

The ornamental design for a bottom and periphery of a cup shaped shoe sole, as shown and described.

DESCRIPTION

FIG. 1 is a side elevational view of one side of the bottom and periphery of a cup shaped shoe sole showing an embodiment of our new design with a translucent section in a portion of the rear part as illustrated by the shading;

FIG. 2 is a side elevational view of the other side of the bottom and periphery of a cup shaped shoe sole shown in FIG. 1;

FIG. 3 is a front elevational view of the bottom and periphery of a cup shaped shoe sole shown in FIG. 1; FIG. 4 is a rear elevational view of the bottom and periphery of a cup shaped shoe sole shown in FIG. 1; FIG. 5 is a bottom plan view of the bottom and periphery of a cup shaped shoe sole shown in FIG. 1;

FIG. 6 is a partial section view taken along line 6—6 of FIG. 5;

FIG. 7 is a sectional view taken along line 7—7 of FIG. 5;

FIG. 8 is a partial sectional view taken along line 8—8 of FIG. 5;

FIG. 9 is a partial sectional view taken along line 9—9 of FIG. 5;

FIG. 10 is a side elevational view of one side of a bottom and periphery of a cup shaped shoe sole showing an alternative embodiment of our new design;

FIG. 11 is a side elevational view of the other side of the bottom and periphery of a cup shaped shoe sole shown in FIG. 10; and

FIG. 12 is a bottom plan view of the bottom and periphery of a cup shaped shoe sole shown in FIG. 11.

The broken line showing of a shoe upper is for illustrative purposes only and forms no part of the claimed design.
